UNITED STATES PATENT OFFICE.

JOHN F. GODFREY, OF ELKHART, INDIANA.

RECLAIMING AND CONVEYING BUCKET.

1,397,509.

Specification of Letters Patent.

Patented Nov. 22, 1921.

Application filed August 23, 1920. Serial No. 405,451.

To all whom it may concern:

Be it known that I, JOHN F. GODFREY, a citizen of the United States, residing at Elkhart, in the county of Elkhart and State 5 of Indiana, have invented certain new and useful Improvements in Reclaiming and Conveying Buckets, of which the following is a specification.

This invention relates to reclaiming and 10 conveying buckets, and particularly to means for releasably locking the dump door there-of in closed position in a manner whereby the door may be tripped for pumping purposes under certain predetermined conditions.

The object of the invention is to provide 15 a simple, durable and efficient reclaiming and conveying bucket in which coöperating parts thereof are operated and controlled in 20 a manner to meet the various requirements for successful commercial operation.

This and other objects are accomplished 25 by means of the arrangement disclosed on the accompanying sheet of drawings, in which—

Figure 1 is a side elevation;

Fig. 2 is a top plan view; and,

Fig. 3 is an end view of a preferred form 30 of my reclaiming and conveying bucket.

The various novel features of my invention 35 will be apparent from the following description and drawings and will be particularly pointed out in the appended claims.

Referring to the figures of the drawings, it 40 will be noted that the bucket includes a body portion 10 for receiving the load, said body portion at one end being provided with a dump door 11, which is pivotally connected at 12 to any suitable part of the body 10.

The dump door 11 normally is held closed 45 by a movably mounted latch 13, which is slidably carried in guide members 14 and 15 secured to the under side of the door, said latch in its latching position engaging a

latch hook 16 on a member 17 secured to the 50 body of the bucket. Surrounding the latch 13 is a coiled spring 18, the outer end of which is secured to the latch and the inner end of which is free with respect to same,

said spring being interposed and operative 55 between the two guide members 14 and 15 and normally holding the latch in locking position. Pivots connected to the inner end of the latch 13 is a link 19, the inner

end of which is pivotally connected at 20 to an intermediate point of a control lever 21,

the inner end of which is pivotally connected at 22 to the door 11. The outer end of the control lever 21 extends outwardly away from the bottom of the door 11 for the 60 purpose of passing into engagement with the ground, or any other object, for tripping the latch 13, whereupon the door 11 swings open under the influence of a load in the body 10 for dumping purposes. When the 65 load has been completely dumped, the door 11 is returned to closed or latched position by oppositely arranged balance springs 23, one end of each of which is operatively connected at the points 24 to the dump door 11 70 and the other end of each of which is operatively connected at points 25 to the body portion 10 of the bucket, said springs 23 preferably being located inside of the bucket. It will be understood that as the 75 door 11 is moved into closed position, the spring-pressed latch 13 automatically passes into engagement with its associated latching hook 16 for locking the door in such position.

For loading the bucket, the same is provided with a variable draft mechanism, including a main central draft member 26 and a plurality of side draft members 27. Preferably the draft member 26 is secured to suitable reinforcing angle members 28 extending lengthwise along one side of the bucket and is provided at one end with a plurality of apertures 29 whereby the side draft members 27 may be selectively secured thereto by means of a pin, bolt, or any 80 other fastening means 30, it being understood that said side draft members at their outer ends are provided with corresponding apertures 31. The side draft members 27 at their inner ends are pivotally connected to the body portion 10 of the bucket, or to straps 32 carried thereby, said straps also having a plurality of apertures 33 for selectively receiving pivot pins 34 which pivotally connect the inner ends of the side 85 draft members 27 to the body portion of the bucket. By means of this draft mechanism, including the members 26 and 27, which may be secured to each other in a plurality of different relative positions, and the side 90 draft members 27 capable of being pivotally secured to the body portion of the bucket in a plurality of different positions, a variable draft may be obtained to meet all of the requirements encountered in commercial 95 usage. The digging end of the bucket is provided with a plurality of teeth 35.

The various parts of the bucket coöperate and are controlled to meet all of the requirements for successful commercial usage.

It is my intention to cover all modifications of the invention falling within the spirit and scope of the following claims.

I claim:

1. A bucket of the class described including a body portion, a latch hook secured to said body portion, a dump door pivotally connected to said body portion, a releasable latch carried by said dump door normally engaging said hook for holding the door in closed position and having an operating lever adapted to be operated for permitting the release of said door for dumping purposes, by engagement with the ground and a balance spring operative between said body portion and door and mounted within the bucket for closing said door after the load has been dumped.
2. A bucket of the class described including a body portion, a dump door therefor, a releasable latch carried by said dump door normally effective for holding the door in closed position and upon being operated re-

leasing said door for dumping purposes, and a balance spring contained within said body portion and operative between said dump door and body portion for returning said door to closed position after it has been opened.

3. A bucket of the class described including a body portion, a dump door therefor, releasable latch mechanism carried by said dump door for normally holding the door in closed position, said mechanism including a movably mounted latch member, a latch guide therefor, a link pivotally connected to said latch, and a control member pivotally connected to said link.

4. A bucket of the class described including a body portion, a dump door therefor, a plurality of draft members capable of being connected to each other in a plurality of relative positions and at least one of said draft members capable of being connected to the body portion in a plurality of different positions for varying the draft.

Signed at Elkhart, Indiana, this 19th day of August, 1920.

JOHN F. GODFREY.
